DESIGN FOR A SHOE

Otto Hasse, Sunnyside, Long Island, N. Y.

Application October 12, 1934, Serial No. 53,587

Term of patent 3½ years

To all whom it may concern:

Be it known that I, Otto Hasse, a citizen of the United States, and a resident of Sunnyside, Long Island, N. Y., have invented a new, original, and ornamental Design for a Shoe, of which the following is a specification, reference being had to the accompany drawing, forming part thereof.

The dominant feature of the present design is the ornamental effect produced by the strap, extending across the instep opening of the shoe in spaced relation to the lower edge of said opening, in combination with the lacing elements.

I claim:

The ornamental design for a shoe, as shown and described.

OTTO HASSE.
